(57) CLAIM

The ornamental design for a robe with nursing pockets as shown and described.

DESCRIPTION

FIG. 1 is a front view of the robe with nursing pockets showing my new design;

FIG. 2 is a first side view of the robe with nursing pockets of FIG. 1;

FIG. 3 is a rear view of the robe with nursing pockets of FIG. 1;

FIG. 4 is a second side view of the robe with nursing pockets of FIG. 1;

FIG. 5 is an enlarged detailed view taken from line 5 in FIG. 1;

FIG. 6 is an enlarged detailed view taken from line 6 in FIG. 5 with the pocket features in an open configuration;

FIG. 7 is a view of an inner side of the robe with nursing pockets of FIG. 1;

FIG. 8 is an enlarged detailed view taken from line 8 in FIG. 7; and,

FIG. 9 is an enlarged detailed view taken from line 9 in FIG. 7.

The dash-dash broken lines in the drawing disclosure depicts features of the robe with nursing pockets that form no part of the claimed design. The dash-dot broken lines depict the boundaries of the enlarged figure views and form no part of the claimed design. In addition, the surface shading illustrated in the figures is provided merely to highlight the contour of the design and is not to be illustrative in texture.

1 Claim, 7 Drawing Sheets
